UNITED STATES PATENT OFFICE.

NATHAN B. HUTTON, OF BARNESVILLE, OHIO.

SAFETY CLOTHES-WRINGER.

1,139,122.

Specification of Letters Patent.

Patented May 11, 1915.

Application filed May 14, 1914. Serial No. 838,566.

To all whom it may concern:

Be it known that I, NATHAN B. HUTTON, a citizen of the United States, and residing at Barnesville, in the county of Belmont and 5 State of Ohio, have invented a new and useful Safety Clothes-Wringer, of which the following specification is a full disclosure.

My invention relates to an improvement in a clothes wringer.

10 The object of the invention is to provide a safety break bar mechanism for separating the rolls instantly in case the hand of the operator becomes accidentally caught between the rolls.

15 I am not the first to propose or devise such a safety provision, but my invention resides somewhat in the detail of the structure, providing a simple mechanism, breaking in a vertical plane, and instantaneously 20 relieving the roll tension simultaneously at each end.

The features of the invention are more fully set forth in the description of the accompanying drawings, forming a part of 25 this specification, wherein:—

Figure 1 is a front elevation showing the normal position. Fig. 2 shows the position of parts at the moment of break, that is, the beginning of the emergency relieving movement.

30 The side pieces 1, 2, and bottom cross-bar 3, are as usual, the geared wringer rolls 4, 5, having bearings in pieces 1, 2, the upper roll 5 being held in vertical slots by tension springs 6 in the side pieces 1, 2. A tension bar 7 rests on the top of said springs to equalize the roll tension. Pieces 1, 2, have pins 8 at their upper ends fitting in slots 9 of the top break bar 10, the set screws 11 in 35 bar 10 engaging downwardly against the opposite ends of tension bar 7, for adjusting the roll tension. The break bar comprises the members 12, 13, the meeting ends having brackets 14, 15, pivotally secured by 40 pivot 16 on the under side of bar 10, the joint being in a vertical plane medial of said bar. The upper portions of said brackets 14, 15 are formed with meeting lugs 17, 18, forming when together a lock detent, the 45 pivoted spring unitary latch 19 having an indent 20, into which the detent projects, as shown in Fig. 1, when the bar is in normal position. In case of an accident, a touch on 50 knob 21, unlatches the joint and the meeting ends of the members 12, 13, fly upward under the influence of the springs 6, the slot

and pin connection at the ends permitting of this movement. The break is in a vertical plane and midway between the side pieces 1, 2, so that the roll tension is instantaneously 60 and simultaneously released.

When the joint is broken, see Fig. 2, the upper roll will rise as bar 7 lifts member 10, the downwardly inclined open end slots permitting said member to slide endwise off 65 of pins 8, as the joint is now flexible and the member urged upwardly by the spring pressure, thus completely releasing the inner roll. When the sections of member 10 are latched into alignment, the rolls are held together under tension.

Having described my invention, I claim:—

1. In a clothes wringer, a frame, tension controlled rolls therein separable when the 75 tension is released, a transversely breakable tension applying bar and an emergency release for breaking the bar.

2. In a clothes wringer, a frame, tension controlled rolls therein, separable when the 80 tension is released, a transversely breakable tension applying bar, means for adjusting the roll tension when said bar is in normal position, and an emergency release for breaking the bar.

3. In a clothes wringer, side pieces, wringer rolls mounted therein and separably held under spring tension, a top cross-bar formed of two pieces hinged together at their meeting ends enabling the meeting 90 ends to move vertically, a snap-latch to normally hold said pieces rigidly in alignment, pin and slot connection between the side pieces and the outer ends of said cross bar pieces, and means whereby the roll tension is controlled by said cross bar when in 95 normal position.

4. In a clothes wringer, side pieces, wringer rolls mounted therein and separably held under spring tension, a top cross-bar 100 comprising two pieces meeting and separating in a vertical plane, brackets on said meeting ends pivoted on the under side, lugs on the upper portions of said brackets constituting a locking detent when the joint 105 is closed, a snap latch on one of said brackets for locking and releasing said lugs, pin and slot connection between the outer ends of said cross-bar, and said side pieces, and means whereby the roll tension is controlled 110 by said cross-bar when in normal position.

5. In a clothes wringer, side pieces,

wringer rolls separably held by the side pieces, tension means on the side pieces, a medially breakable bar having a pin and slot connection with the side pieces, 5 a latch for the breakable portion of said bar to hold the ends of the bar in alinement and adapted to constitute an emergency release, and means whereby the alinement of the breakable sections of the bar holds the 10 rolls under tension and automatically re-

leases them upon unlatching said breakable bar.

In witness whereof, I hereunto subscribe my name, as attested by the two subscribing witnesses.

NATHAN B. HUTTON.
